UNITED STATES PATENT OFFICE.

WALTER H. KIRKBRIDE, OF PALO ALTO, CALIFORNIA.

CURVE RAIL PLATE.

Application filed May 7, 1924. Serial No. 711,623.

To all whom it may concern:

Be it known that I, WALTER H. KIRKBRIDE, a citizen of the United States, residing at Palo Alto, in the county of Santa Clara and State of California, have invented certain new and useful Improvements in Curve Rail Plates, of which the following is a specification.

My invention relates, in general, to fastening means by which railway-rails are secured to cross-ties, and, in particular, it relates to and consists in a novel assemblage or combination of the several members of a fastening comprising as one of said members a supplementary plate, which from its especial use on curves may properly be termed a curve rail-plate, though it is to be understood that it may also be used at other points as for example on tangent tracks, or wherever conditions may develop a necessity for its presence.

One object of my invention is to prevent the widening of the track-gauge, a tendency to which is especially noticeable on curves due to the outward pressure on the rail.

Another object is to lessen the tendency to injure to the fibres of the ties next to the spike holes, by a more even distribution to the tie of the rail-pressure.

Another object is to protect the tie from occasional flange cutting due to derailment.

Another object is to check any tendency of the standard tie-plate to work outwardly under traffic and thus widen the gauge of track.

Another object is to relieve the excessive pressure on the spikes and thus protect the tie from mechanical wear.

In the accompanying drawings, to which reference is hereby made, I illustrate and shall now fully describe my invention, it being understood that changes in form and detail may be made without departing from the spirit of the invention as defined in the claims hereunto appended.

In the drawings, Fig. 1 is a view partly in section of a railway rail fastening embodying my invention, the curve rail-plate being in its simplest form.

Fig. 2 is a plan of the same.

Fig. 3 is a side elevation, the rail being in cross section, of a fastening embodying my invention, the curve rail-plate being in its more developed form.

Fig. 4 is a plan of the same.

Fig. 5 is a plan of the metal blank from

which the developed curve rail-plate of Figs. 3 and 4 is made.

1 is a railway-rail; 2 is a cross-tie; 3 is the ordinary or standard tie-plate; and 4 the spikes, the heads of which engage the foot flanges or base of the rail and the bodies of which pass down through the tie-plate and penetrate the tie.

5 is a supplementary plate placed between the tie and the tie-plate. In its simplest form, as shown in Figs. 1 and 2, this plate 5 is a flat steel plate. The rail-engaging spikes 4 which pass through the tie plate 3, also pass through this plate 5 and said plate 5 is additionally secured to the tie by means independent of said rail-engaging spikes, as for example, by screw spikes, or by the lag screws 6 as here shown. In its more developed form, when greater security is desired, the supplementary plate 5 assumes the shape and structure shown in Figs. 3 and 4. It is best made from a blank shown in Fig. 5 and has an upturned outer end flange or stop 5' and downturned side flanges or members 5''. The outer edge of the tie-plate 3 engages the end stop 5' as seen in Figs. 3 and 4, thus checking any tendency for the tie-plate to work out under traffic and widen the gauge of track. The side flanges or members 5'', which, as shown, are preferably, though not essentially, of a form widening rearwardly, fit over the sides of the tie, and are fastened thereto by a through bolt 7. This developed curve plate 5 is also further fastened by means independent of the rail engaging spikes as for example by the spike 8.

I claim:

1. In a railway-rail fastening, in combination with a rail, a tie, a tie-plate underlying the rail, and spikes engaging the rail and passing through the tie-plate into the tie, a supplementary plate underlying the tie-plate and resting on the tie, the rail engaging spikes passing through said supplementary plate; and means for securing said supplementary plate to the tie independently of the rail-engaging spikes.

2. In a railway-rail fastening, in combination with a rail, a tie, a tie-plate underlying the rail, and spikes engaging the rail and passing through the tie-plate into the tie, a supplementary plate underlying the tie-plate and resting on the tie, the rail engaging spikes passing through said supplementary plate and said supplementary plate hav-

ing a stop at its outer end against which the outer edge of the tie-plate abuts; and means for securing said supplementary plate to the tie independently of the rail-engaging spikes.

3. In a railway-rail fastening, in combination with a rail, a tie, a tie-plate underlying the rail, and spikes engaging the rail and passing through the tie-plate into the tie, a supplementary plate underlying the tie-plate and resting on the tie, the rail engaging spikes passing through said supplementary plate and said supplementary plate having side members engaging the sides of the tie; and means for securing said supplementary plate to the tie independently of the rail-engaging spikes.

4. In a railway-rail fastening, in combination with a rail, a tie, a tie-plate underlying the rail, and spikes engaging the rail and passing through the tie-plate into the tie, a supplementary plate underlying the tie-plate and resting on the tie, the rail engaging spikes passing through said supplementary plate and said supplementary plate having side members engaging the sides of the tie; a bolt passing through said side members and tie; and other fastening means, independent of the rail-engaging spikes, for securing said plate to the tie.

5. In a railway-rail fastening, in combina-

tion with a rail, a tie, a tie-plate underlying the rail, and spikes engaging the rail and passing through the tie-plate into the tie, a supplementary plate underlying the tie-plate and resting on the tie, the rail engaging spikes passing through said supplementary plate and said supplementary plate having a stop at its outer end engaging the outer edge of the tie-plate, and having also side members engaging the sides of the tie; and means for securing said supplementary plate to the tie independently of the rail-engaging spikes.

6. In a railway-rail fastening, in combination with a rail, a tie, a tie-plate underlying the rail, and spikes engaging the rail and passing through the tie-plate into the tie, a supplementary plate underlying the tie-plate and resting on the tie, the rail engaging spikes passing through said supplementary plate and said supplementary plate having a stop at its outer end engaging the outer edge of the tie-plate, and having also side members engaging the sides of the tie; a bolt passing through said side members and tie; and other fastening means, independent of the rail-engaging spikes, for securing said plate to the tie.

In testimony whereof I have signed my name to this specification.

WALTER H. KIRKBRIDE.
